UNITED STATES PATENT OFFICE

DYKE F. ENGLEMAN, OF NEW YORK, N. Y.

DESIGN FOR AN AUDITORIUM-CABINET.

45,865.

Specification for Design.

Patented June 2, 1914.

Application filed February 4, 1914. Serial No. 816,632. Term of patent 7 years.

To all whom it may concern:

Be it known that I, DYKE F. ENGLEMAN, a citizen of the United States, residing at New York, in the county of New York and State of New York, have invented a new, original, and ornamental Design for an Auditorium-Cabinet, of which the following is a specification, reference being had to the accompanying drawing, forming part thereof.

The figure is a perspective view of an auditorium cabinet, showing my new design.

I claim:

The ornamental design for an auditorium cabinet, as shown.

DYKE F. ENGLEMAN.

Witnesses:

JOHN KECK,
KURS WEHEH.
